(57) **CLAIM**

The ornamental design for a container with lid, as shown and described.

DESCRIPTION

FIG. 1 is a perspective view illustrating our design for a container with lid.

FIG. 2 is a front view thereof.

FIG. 3 is a right side view thereof.

FIG. 4 is a rear view thereof.

FIG. 5 is a left side view thereof.

FIG. 6 is a bottom view thereof.

FIG. 7 is a top view thereof; and,

FIG. 8 is an exploded perspective view, with the lid removed from the base.

The woodgrain lines throughout the lid in FIGS. 1, 2, 3, 4, 5, 7 and 8 are simulative of a woodgrain pattern (whether an actual woodgrain or a simulated woodgrain) and do not represent a particular woodgrain pattern. The broken lines in the drawings, including the lines that are simulative of the woodgrain pattern, illustrate portions of the article that form no part of the claimed design.
